CLAIM

The ornamental design for a mug warmer, as shown and described.

DESCRIPTION

FIG. 1 is a first perspective view of a mug warmer showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof.

FIG. 9 is an enlarged view of the selected portion 9in FIG. 1;

FIG. 10 is an enlarged view of the selected portion 10in FIG. 5; and,

FIG. 11 is an enlarged view of the selected portion 11in FIG. 7.

The dash-dash broken lines shown in the drawings depict portions of the mug warmer that form no part of the claimed design. The dot-dash broken lines in FIGS. 1, 5, 7, 9, 10 and 11 illustrate the periphery of the enlarged views of the mug warmer and form no part of the claimed design.

1 Claim, 11 Drawing Sheets
